UNITED STATES PATENT OFFICE

114,952

DESIGN FOR A POWER PLANT UNIT

Fred Jervis, Los Angeles, Calif., assignor to
Bardco Corporation of America, Los Angeles,
Calif., a corporation of California

Application March 10, 1938, Serial No. 76,032

Term of patent 14 years

To all whom it may concern:

Be it known that I, Fred Jervis, a citizen of the United States of America, residing at Los Angeles, in the county of Los Angeles and State of California, have invented a new, original, and ornamental Design for a Power Plant Unit, of which the following is a specification, reference being had to the accompanying drawing, forming part thereof.

In the drawing, Fig. 1 is a front perspective of a power plant unit embodying my new design; and Fig. 2 is a rear perspective of said design, taken from the other end.

I claim as my invention:

The ornamental design for a power plant unit, as shown,

FRED JERVIS.
